UNITED STATES PATENT OFFICE.

SIGMUND STERNAU, OF NEW YORK, N. Y.

DESIGN FOR A KETTLE.

SPECIFICATION forming part of Design No. 23,763, dated November 6, 1894.

Application filed October 6, 1894. Serial No. 525,178. Term of patent 3½ years.

To all whom it may concern:

Be it known that I, SIGMUND STERNAU, a citizen of the United States, residing in New York, county of New York, and State of New York, have invented and produced a new and original Design for Kettles, of which the following is a specification, reference being had to the accompanying drawing, which shows the kettle in perspective.

10 The leading or characteristic feature of my design is the body of the kettle shaped as shown, flared outwardly at and near its upper side and ending at its lower side in a small shallow base.

A is the kettle body, having the central circular rib a, and at its top flared outwardly as at a' and a'', the lower portion of the body developing or ending in an extremely shallow base a''.

B represents the spout, C the handle, having the shape shown and D the top or cover.

What I claim is—

The design for a kettle, as hereinabove shown and described.

SIGMUND STERNAU.
